DESIGN FOR A SHOULDER BAG OR SIMILAR ARTICLE

Maurice J. Kruger, Brooklyn, N. Y., assignor to Kruger, Ressner & Arner, Inc., New York, N. Y., a corporation of New York

Application June 19, 1939, Serial No. 85,561

Term of patent 3½ years

To all whom it may concern:

Be it known that I, Maurice J. Kruger, a citizen of the United States, and a resident of Brooklyn, county of Kings, and State of New York, have invented a new, original, and ornamental Design for a Shoulder Bag or Similar Article, of which the following is a specification, reference being had to the accompanying drawing, forming a part thereof, wherein:

Fig. 1 is a top plan view of a shoulder bag or similar article, embodying my new design;

Fig. 2 is a front elevational view thereof with the handle broken away for convenience of illustration;

Fig. 3 is an end elevational view thereof, and

Fig. 4 is a rear elevational view thereof with the handle shown broken away.

I claim:

The ornamental design for a shoulder bag or similar article, substantially as shown.

MAURICE J. KRUGER.
